[57] CLAIM

The ornamental design for an organizer with horizontal central storage sections and end vertical storage sections, as shown and described.

DESCRIPTION

FIG. 1 is a front, top, right side perspective view of an organizer with horizontal central storage sections and end vertical storage sections, showing my new design;

FIG. 2 is a top plan view thereof;

FIG. 3 is a front elevational view thereof;

FIG. 4 is a left side view thereof, the right side view being identical;

FIG. 5 is a rear elevational view thereof; and,

FIG. 6 is a bottom plan view thereof.
